UNITED STATES PATENT OFFICE.

JOHN C. BOYTON AND ORIS H. NICKERSON, OF CLEVELAND, OHIO.

SWITCH-BOX.

1,249,313.

Specification of Letters Patent. Patented Dec. 11, 1917.

Application filed January 23, 1914. Serial No. 813,844.

To all whom it may concern:

Be it known that we, (1) JOHN C. BOYTON, (2) ORIS H. NICKERSON, citizens of the United States, residing at Cleveland, in the 5 county of Cuyahoga and State of Ohio, have invented a certain new and useful Improvement in Switch-Boxes, of which the following is a full, clear, and exact description, reference being had to the accompanying 10 drawings.

This invention relates to switch boxes, such as are used in interior electric light wiring, for the housing or accommodation of electric light switches; and especially to that 15 type of box which comprises a body portion and removable sides, whereby two or more body portions may be connected to produce a box for the accommodation of two or more electric switches, the sides being omitted, in 20 such a construction, between the adjacent body portions.

The objects of the invention are to provide a box of the above character which is of simple construction; which is comparatively 25 cheap of production; and which can be quickly and easily converted from a single switch box to a multiple switch box for the accommodation of a number of electric switches, without the use of special tools; 30 and which, either as a single or a multiple switch box, will afford an unobstructed cavity of maximum dimensions as compared with its exterior dimensions.

Further objects of the invention are to 35 provide a switch box of this character which comprises a body portion and removable sides, all of which are formed of sheet metal stampings, and to provide interlocking means between the body portion and the 40 removable sides of such character and arrangement as will render said sides interchangeable and will enable the joining of two or more body portions for the production of a multiple switch box.

45 The above objects we attain by the construction illustrated in the accompanying drawings forming a part hereof, wherein Figure 1 represents a perspective view of our improved switch box; Fig. 2 is a similar 50 view of the box with the sides removed and spaced from the body portion in order to clearly illustrate certain structural details; and Fig. 3 represents a front elevation of a 55 multiple switch box made up of three body portions and two sides.

The body portion of the box comprises end walls 1 and 2 and a rear wall 3, the end walls and the rear wall being connected by the inclined walls 4. The last mentioned walls are provided with the usual "knock 60 out" plugs 5 which close openings through which wires may be led into the box.

Extending laterally from one edge of the end wall 1 is the tongue 6 which has its free end turned downward, as shown at 7, it being noticed that the underneath surface of the horizontal portion of the tongue 6 is substantially in the plane of or slightly above the top surface of the wall 1. A tongue 8, identical to the tongue 6 and having an upturned end 9, projects from the opposite side of the bottom wall 2. Near its edge opposite the tongue 6, the wall 1 is provided with a slot 10, the same being in transverse alignment with the tongue and 75 being of a width and length which corresponds, approximately, to the width and thickness of the downturned portion 7 of the tongue 6. It will be mentioned at this time, that this slot is spaced from the adjacent edge of the wall 1 a distance equal to the thickness of one of the removable sides of the box and that the inner surface of the downturned portion 7 of the tongue 6 is spaced from the adjacent edge of the wall 1 80 a corresponding distance. The end wall 2 of the body portion of the box is also provided with a slot 11 identical to the slot 10 of the wall 1, and the slot 11 is located, with respect to the tongue 8, precisely as the slot 90 10 is situated with respect to the tongue 6. Comparatively large headed screws 12 and 13 are threaded through the end walls 1 and 2, respectively, adjacent the aforesaid slots, the distance between the slots and the screws 95 being such as will cause the head of the screw to project slightly over the slot.

The removable sides 14 and 15 are identical, each consisting of a metallic plate which is of a shape corresponding substantially to 100 the side of the body portion of the box. The lower edge of the side 14 is provided with a notch 16 for cooperation with the tongue 8, the horizontal wall of the notch being substantially in line with the outside 105 surface of the wall 2 when the parts are assembled. A tongue 17 extends from the upper edge of the plate 14 and is in vertical alignment with the notch 16, the width of said tongue being the same as that of the 110

previously mentioned tongues 6 and 8. The tongue 17 projects laterally from the top edge of the plate 14 and its end is bent downward in a plane parallel with the said 5 plate, the adjacent surfaces of the plate and the tongue being spaced apart a distance corresponding to the thickness of the plate 14 and the underneath surface of the horizontal portion of the tongue being in substantially the plane of the upper edge of the 10 plate. The upper edge of the side 15 is notched at 18, and a tongue 19 projects from its lower edge.

With the parts constructed in accordance 15 with the foregoing description, it will be seen that the box is assembled as follows:— The plate 14 is applied to the side of the body portion of the box by inserting the downturned end of the tongue 17 into the 20 slot 10 of the end wall 1. The notch 16 is then placed over the tongue 18 and the plate 14 is moved downwardly until the substantially horizontal portion of the tongue 17 rests upon the surface of the wall 1, and the 25 horizontal wall of the notch 16 is in contact with the tongue 8, the upturned portion of said tongue lying against the outer surface of the side 14. It will be understood, of course, that, during this operation, the 30 screw 12 is unscrewed a sufficient distance to permit the tongue 17 to be easily inserted within the slot 10. When the side is in position, the screw 12 is screwed inward until its head is in firm engagement with the 35 tongue 17, thereby securely locking the plate against endwise movement, the lateral movement of the plate with respect to the body portion being prevented by the interlocking of the tongue 17 with the slot 10 and the 40 engagement of the upturned portion 9 of the tongue 8 with the outer surface of the side. In like manner, the side 15 may be applied to the opposite side of the box, the screw 13 being used to lock the latter side plate in 45 position.

From the fact that the removable sides are identical, (only that one is inverted with respect to the other) and that the same may be said of the opposed vertical sides of the 50 body portion of the box, it is obvious that said removable sides are interchangeable, and that, to produce a multiple box of two or more body portions, it simply requires the interlocking of the tongues 6 with the 55 slots 10 and the tongues 8 with the slots 11 of adjacent body portions, the assemblage being held as a unitary structure by the bearing of the screws 12 and 13 upon the adjacent tongues 6 and 8, respectively. The 60 ends of the "gang" box are closed by the side plates 14 and 15, as shown in Fig. 3.

Projecting upward and downward from the front edges of the end walls 1 and 2, respectively, are ears 20 having threaded 65 apertures 21 for the reception of screws

whereby a face plate may be secured to the box; and the end walls 1 and 2 are also provided with threaded apertures 23 for screws whereby securing brackets of any approved type may be applied to the box, it 70 being deemed advisable to omit said brackets from the drawings in order to prevent confusion. The sides 14 and 15 are provided with "knock out" plugs 14^a and 15^a, respectively.

75

While we have described our box as consisting of a body portion and side plates, it is obvious that a demand will arise for body portions separate from the side plates, for use in the production of multiple boxes; 80 and we wish it to be understood, therefore, that our invention comprehends an article of manufacture consisting only of such body portion.

Having thus described our invention, what 85 we claim is:

1. A box for the purpose described comprising a body portion having end walls each of which is provided with a permanent tongue, the tongues projecting from the diagonally opposed side edges of said end walls, and each wall being also provided with an opening, side plates which have notches for the reception of the tongues and projections which are arranged to occupy the aforesaid 95 openings, and means permanently carried by the end plates and located to one side of and adapted to engage the projections when the same occupy the slots thereby to hold the side plates against movement with respect to the body portion.

2. A box for the purpose described comprising a body portion having end walls each of which has a permanent tongue projecting from one of its side edges, each tongue having a lateral extension which is spaced from the adjacent edge of the wall, each end wall being also provided with an opening, side plates which have notches that open toward the end of the plate for the reception of the 105 aforesaid tongues and projections which extend in the direction of the notched ends of the respective plates and which are adapted to occupy the aforesaid openings, and means upon the body portion of the box 115 which are arranged to engage the aforesaid projections to prevent endwise movement of the plates.

3. A box for the purpose set forth comprising a body portion having end walls 120 provided each with an integral tongue, the tongues projecting from the diagonally opposed side edges of said end walls, each tongue having a lateral extension which is spaced from the adjacent edge of the wall, 125 each end wall being provided also with an opening which is in lateral alinement with its tongue and which is located near its edge opposite the edge from which the tongue projects, side plates having notches for the 130

reception of the aforesaid tongues and projections which are adapted to occupy the aforesaid openings, and screws threaded into the end walls and arranged to repose alongside the projections with their heads overlying the same.

In testimony whereof, we hereunto affix

our signatures in the presence of two witnesses.

JOHN C. BOYTON.
ORIS H. NICKERSON.
